UNITED STATES PATENT OFFICE.

WILLIAM P. ANDERSON, OF DAYTON, OHIO, ASSIGNOR TO THE DAYTON ENGINEERING LABORATORIES CO., A CORPORATION OF OHIO.

CIRCUIT-CONTROLLER.

1,168,371.

Specification of Letters Patent. Patented Jan. 18, 1916.

Application filed September 12, 1912. Serial No. 719,997.

To all whom it may concern:

Be it known that I, WILLIAM P. ANDERSON, a citizen of the United States, residing at Dayton, county of Montgomery, and 5 State of Ohio, have invented certain new and useful Improvements in Circuit-Controllers, of which the following is a full, clear, and exact description.

This invention relates to a controller 10 switch for selective electrical distribution, whereby various connections may be made and broken, to secure the accomplishment of certain predetermined results.

One of the primary objects of the present 15 invention resides in the provision of a switch, which will embody means for assuring a constant and continued electrical contact between the coöperating members.

A further object of the present invention 20 is to provide a switch, wherein the operation thereof will be made more efficient and the liability of inoperativeness reduced. This is attained by providing means which tend to compensate for inaccuracies present in the 25 elements comprising the switch and which therefore facilitate the correct actuation of the various parts.

Further objects and advantages of the present invention will be apparent from the 30 following description, reference being had to the accompanying drawing, wherein a preferred form of one embodiment of my invention is disclosed.

Figure 1 is a top plan view of a controller 35 switch, embodying the present invention. Fig. 2 is a longitudinal sectional view taken on the line 2—2 of Fig. 3. Fig. 3 is a view in end elevation. Fig. 4 is a detail side elevation view of the movable element of the 40 controller switch. Fig. 5 is a detail elevation view of one of the contact plates of the movable element shown in Fig. 4. Fig. 6 is a detail view of one of the stationary elements.

45 The embodiment of the switch shown in the accompanying drawings, is especially adapted to be employed in electrical systems of the character set forth in my co-pending applications, filed April 17, 1911, Serial No. 50 621,512, and Serial No. 633,443, filed June 15, 1911.

In the embodiment of the switch shown in the accompanying drawings, the movable or swinging member is provided with a series 55 of contact fingers which in turn are so ar-

ranged that upon the shifting thereof into operative position, they will engage and give a positive contact with the coöperating contact plates which comprise one set of stationary elements of the controller. By this 60 action of the controller it will be obvious that one set of electrical connections may be made by shifting the switch into one of its operative positions, and that this set of connections may be broken by returning the 65 movable member to its neutral or "off" position, and that a second or different set of electrical connections may be established by moving the controller to its second operative position. 70

Referring to the drawings and more particularly to Figs. 1, 2 and 3, the numerals 20 and 21 designate the end frames of the controller. The frame 21 has a series of four rods 24, extending therefrom, two of 75 these rods being positioned on opposite sides of the inner face of the frame and in superposed relation. These rods form supports for the stationary members and also coöperate with suitable fastening means, such as is 80 shown by the bolts or screws 23, for securely holding the various elements of the controller in assembled position. These fastening pieces 23 have enlarged heads which fit within counter-sunk portions formed in the 85 outer face of the plate 20, and enter into and engage with the threaded internal bores formed in the ends of the rods 24. The rods 24 are adapted to support certain of the current conductive elements of the switch and 90 inasmuch as these elements may form parts of different circuit connections it is desirable that they be insulated from these rods. Each of these rods is therefore provided with an insulating covering 25, in the present instance consisting of a tube within 95 which the rod is adapted to fit. It will be understood that this controller may consist of any number of contact plates, and that they may be arranged in any suitable relation to effect the various electrical connections for performing the different functions desired, and that therefore the construction and arrangement of the contact fingers and their adjacent insulating or conducting elements which may be so arranged for effecting the opening or closing of certain circuits, or performing other functions, should not be held to limit the scope of the present invention as specifically described. 100 105 110

The stationary contact elements may be of any suitable contour, it only being necessary that one portion thereof is in such position that it may be engaged by the movable contact elements of the controller. In the present instance, the movable elements 26, of the controller, are mounted as a single unit, which has a main shaft 27, pivotally secured between the frame plates 20 and 21. This main shaft or rod 27 is provided with a covering of insulation 28, upon which the contact elements or fingers 26 are mounted. In order that the contact fingers may be supported in an efficient manner, so as to assure, within certain limits, an accurate assembling of the different parts, a central supporting member 29, which extends parallel to the shaft 27, is fixedly secured to the pivoted rod or shaft 27, by means of the connecting plates 30. Each of the movable contact elements 26, of the present controller switch, comprises a pair of metallic blades of limited flexibility or resiliency, spaced apart a certain distance so that upon coming into contact with the single coöperating stationary elements of the controller, they will be forced apart a sufficient distance to slip over and tightly press against or engage with the stationary blades.

The specific construction of the embodiment of the movable contact elements shown in detail in Fig. 5, comprises a pair of blades 31, each of which has an enlarged lower portion 32, as shown in Fig. 5, wherein an annular opening is formed as at 33, for permitting the elements to be slipped over the shaft 27, and its insulating sleeve 28. Directly in alignment with this opening 33, and intermediate the ends of the plate 31, there is formed a second opening or perforation 41, for permitting the assembling of the contact blade on the upper support bar 29; the contact blade itself being enlarged, adjacent to the portion wherein this second perforation or opening 41 is formed, in order to give sufficient strength and rigidity to the blade. The upper or free end of each of these blades which make up the various contact elements 26, is beveled or flanged away from its coöperating blade, as at 34, so as to facilitate the engagement of the movable and stationary elements.

While certain stationary contact elements designated by the numeral 42, have heretofore been described as coöperating with the movable contact elements 26, it should be clearly understood that the present invention relates primarily to the combination of the movable contact elements, with certain other stationary contacts or conductive straps 45, which are entirely apart from the contact elements 42, and which are in constant contact with the lower portion of the

movable contact elements 26, adjacent to their point of engagement with the pivoted shaft 27. These conductive strap or terminal connections are clearly shown in Fig. 2, and are, as stated above, designated by the numeral 45. The various conductive straps are fixedly mounted on the bars or rods 24, and are insulated from each other and from the stationary contact elements 42, by means of insulated washers or sections 46. These conductive straps have an inwardly projecting end portion which is provided with an annular opening 47, which has an entrance 48 of sufficient extent to permit the strap to be slipped over the rod 27, and its insulating sleeve 28. Each of these conductive straps 45 are adapted to be interposed between the blades of one of the movable contact elements 26, and to be in continuous contact making position, with each of said blades. The various contact elements 26 are completely insulated from each other, by means of the insulating washers 48. It has been found, however, that, if the entire space between the adjacent movable contact elements 26, is completely filled with any insulating material, then because of the inaccuracies in machining the various parts and also in assembling the said parts, and also because of atmospheric effects on the various kind of insulation, it often occurs that a binding effect will be created between the blades 31 and the movable contact elements 26, and the conductive straps 45, in such a manner that it will be practically impossible to shift the movable contact elements from one of their operative positions into another. That is, in the machining and assembling of these elements, slight inaccuracies may occur, which will cause the stationary members to lie slightly out of their proper position relative to the movable parts. It has also been found that where the stationary members are at all times supposed to be in contact with a portion of the movable contact elements, variations in the size and contour of the conductive or insulating elements, caused by atmospheric or other conditions, should preferably be compensated for. This compensation is advisable to prevent such a binding effect between the stationary and movable elements as will prevent the free operation of the movable elements. In order to take care of this condition, a series of resilient elements, in the present case being shown as coil springs 52, are interposed between the insulating washers 46, in such a manner that the lower portion of the movable contact elements 26 will be constantly maintained in contact-making position relative to the conductive strip 45. Now, if any variations or inaccuracies occur or are present, the compression or expansion of the springs 52, together with the inherent flexibility or

resiliency of the blades 31, will take care of the same, and still maintain a good electrical contact therebetween, and at the same time permit the free operation of the switch.

5 The above description will make clear the structure and functions of the lower portion of the movable contact elements 26, relative to the conductive straps 45. The upper portion of the movable contact elements 26, as has been stated heretofore, comprises a pair of blades, having their co-adjacent edges beveled or bent back in an opposite direction, so as to permit the contact members to readily engage with the stationary contact members of the switch, when the movable elements are shifted from one position to another, even though the stationary members and the movable contact elements are not mounted in exactly 10 their proper relative positions. This compensating effect is further enhanced by the fact that the upper portions of the movable contact elements are slightly resilient.

As shown in Figs. 1 and 2, various combinations relating to the making and breaking of circuits, may be secured by any suitable re-arrangement of the terminals 51; and connecting straps such as 54, may be employed to connect the various conductive elements, to secure the above functions, or in order to effect various other functions.

In order that the claims may be clear, the term "stationary conductors" will be used to refer to the conductive straps 45, in order to differentiate from the stationary contacts 42.

While the present invention has been described with relation to a controller which 40 may be preferably used with electrical systems, such as has been described and shown in my co-pending applications heretofore mentioned, it will be appreciated that the elements and combinations of elements comprising the present invention, may be employed with various other electrical systems, and may be so altered and arranged as to be applicable to practically any electrical system, wherein the closing and opening of certain 45 circuits is desired, without departing from the spirit and scope of the present invention, as has been set forth in the appended claims.

50 What I claim is as follows:

1. In a controller switch, the combination of a plurality of sets of movable contacts, of stationary conductors one of which is associated with each set of movable con-

tacts; and resilient means positioned between the adjacent sets of movable contacts for maintaining one contact of each of said adjacent sets in electrical connection with its respective coöperating stationary conductor.

2. In a controller switch, the combination with a series of sets of movable elements, each comprising a pair of blades having free ends; of a series of stationary conductors, each positioned intermediate the blades of one of said sets of movable contacts; a plurality of sets of stationary contact elements oppositely disposed, and adapted to be engaged by the free ends of the movable contact elements; and resilient means interposed between each set of movable elements, whereby the blades of each 75 set of movable elements will be yieldingly maintained in contact with the stationary conductors.

3. In a controller switch, the combination with a frame, of a series of sets of movable contacts, each comprising a pair of blades mounted thereon; a series of stationary conductors one of which is positioned intermediate each pair of blades also mounted on said frame; and resilient means 85 positioned between the adjacent pairs of blades and adapted to maintain one blade of the said adjacent pairs in contact making position with the respective stationary conductors.

4. In a controller switch, the combination with a frame, of a plurality of stationary contact elements mounted thereon, each comprising a single blade; of a series of sets of movable contacts, each comprising a 95 pair of resilient blades having free ends which coöperate with the said stationary contact elements movably mounted in said frame; a plurality of stationary conductors also mounted on said frame and coöperating 100 with said movable contact elements; insulating means between the adjacent plates of each of said movable contacts; and resilient means interposed between the adjacent insulating means, adapted to compensate for 105 variations in the size and location of the insulating means.

In testimony whereof I affix my signature in the presence of two subscribing witnesses.
